UNITED STATES PATENT OFFICE

KARL DAMMANN, OF ESSEN, GERMANY

BUILDING ROADS

No Drawing. Application filed July 2, 1928, Serial No. 290,041, and in Germany July 11, 1927.

My invention relates to a method of building roads.

The simplest and cheapest means to treat ordinary metalled roads so that they resist the influences of the weather and in particular the sucking action of the automobiles consists, as well known, in applying a tar surface thereon. According to the experience hitherto prevailing, this tarring method affords its greatest effect, if the small stones of the ballast layer, to be tarred, lie freely on the surface of the road, but are firmly embedded in sand or an other binding means. It is however very seldom that a road is in this condition, at least not to its entire extent. On the contrary, in the most cases the stones are partly covered by a mud layer or they are loosened, so that this layer is removed by the traffic or by means of sharp brooms. In both cases, however, the effect of the surface tarring is doubtful.

But even in the best of cases this thin protective layer obtained by tarring the ballast layer in the ordinary manner is not able to resist heavy traffic for an appreciable time. For this reason recently the tar layer has been covered, with any fine material bituminized in any suitable manner, to obtain a stronger wear layer instead of being covered with sand or small rubble. But as experience has shown, this so-called carpet has not the required degree of resistance, if the ballast cover to be tarred does not fulfil the conditions mentioned above.

Therefore with all roads that are exposed to heavy traffic the so-called internal tarring or asphalting method has been employed hitherto, by either enveloping the ballast stones with bitumen before spreading them out, or by subsequently soaking the spread stones with tar or asphalt. The advantage obtained by this method, however, does not correspond to its expense, as the sole effect obtained thereby consists in the fact, that a solid and smooth bottom layer is produced for the wear layer to be applied thereon as above mentioned. The resistance to wear, however, and thus the life of the road cover only depends on this uppermost wear layer,

so that the latter must be renewed from time to time.

Therefore, since the employment of the so-called emulsions the ballast has been partly filled out with sand or small rubble for economy's sake, and only the upper half of the ballast layer has been soaked with the emulsion. This is the so-called half-soaking method. But even in this case the consumption of the comparatively costly emulsion is considerable and this method is therefore expensive.

Now my invention constitutes a farther step in this direction by not soaking the ballast layer at all. It is based upon the perception and experience that a road ballast layer filled out with ordinary sand or the like gets the desired strength merely by the compression due to the traffic, provided its surface is protected originally in a suitable manner from the loosening and soiling action of the traffic, and accordingly a bituminous binding means within the layer is absolutely superfluous. It is far more useful to use the bitumen saved in this manner to produce a satisfactorily upper wear layer.

According to my invention the interstices of the ballast layer are first completely filled with sand or the like. This may be done either by rolling the metal stones into a sand bed or by rinsing the sand in the usual manner with water between the stones during rolling. In so doing, however, in contradistinction to the hitherto usual mode of construction the stones are not covered with sand, and sand happening to deposit itself on the surface is carefully washed up or swept off, so that the surface of the stones is exposed. Thereupon an ordinary surface tar layer is applied to the road with the usual hot tar or bitumen. To this end the road needs not to be absolutely dry, it will be sufficient, on the contrary, that the surface of the stones is just beginning to dry. For hot bitumen or tar adheres very well even to moist stones, provided it has a sufficiently low melting point. Of course, also the above-mentioned expensive emulsions may be used for this surface coat, but this is not necessary, since no penetration of the applied material in the inter-

stices is aimed at. But even when emulsion is used, much less emulsion would be consumed due to the interstices previously having been completely filled with sand. Thereupon the 5 surface coat is covered in the usual way with sand or better with small rubble and the road is thoroughly rolled down anew and is then ready for the traffic. The effect of this simple method is very astonishing. The coating material adheres on the surface of the metal 10 stones and penetrates in the interstices, whereby the stones are supported against one another. The surface hardens and closes itself very quickly and becomes flat as an asphalt coat. The complete consolidation and 15 tightening of the ballast layer takes place by the traffic without being disturbed by the formation of rolling stones, and the coating material resists the sucking action of automobiles. 20

The substantial and efficacious difference between my present method and those hitherto employed thus resides in the fact, that the ballast layer is not consolidated, previous to 25 its being tarred on the surface, by the traffic, but on the contrary this surface tarring is done at once, when the surface of the stones are exposed and the ballast layer is not yet completely hard. In contradistinction thereto, according to the meaning hitherto prevailing, the absolute hardness of the ballast to be tarred was the main preliminary condition for the success and this is the case still with all standard road covers. For, with the latter a further compression does not take place, 30 the cover is already completely hard. Now when in that case the stones have become loose on the surface due to the binding material having been sucked out, they will not become 35 solid again by tarring or soaking, as the sticking power of the tar or bitumen is insufficient therefor and a repeated mutual propping of the stones is impossible owing to the hardness of the lower portion of the ballast. As against 40 this definite compression takes place much more quickly and thoroughly by the traffic on a fresh road cover produced according to my invention.

Roads constructed according to my invention 50 resemble in appearance and nature the first class tarred macadam roads and may be permanently maintained in satisfactory condition like these by periodically tarring them. True they require a somewhat greater attention in maintaining them, as they at once lose the character of a bituminized road at the places where the thin surface coat is worn out.

Therefore with all more frequented roads 60 it will be of advantage to cover the surface coat, instead of simply applying sand, with a thicker wear layer of a bituminized fine mineral. An easily compressible mass will be particularly well suited for this purpose, 65 that is a mass to be applied in cold state,

the compressing and solidification of which by the traffic takes place in unison with that of the ballast layer. After the compression has been terminated, the ballast layer and the wear coat form a completely coherent, 70 solid and undisplaceable mass the life of which depends only upon the wear by the traffic as that of any first class sand-asphalt cover.

As to the details of execution, my described 75 method may be modified of course in different respects. As a complete filling of the interstices between the metal stones without soiling their surfaces will not be possible in any weather. Slightly bituminized sand may 80 be used to ultimately fill the interstices. In this manner the bituminous protective layer is increased and too much tar is prevented from penetrating into the ballast.

Furthermore, to prevent an eventual excess of tar from exuding through the bituminous wear layer and, to save at the same time material for the latter, the tar coat may be first treated with a little sand or rubble, whereupon the wear coat is applied. When 90 still greater movement of the ballast of new roads are to be expected due to the ground giving way, the surface coat is preferably first only sanded and the proper wear layer is applied only later on, when the ground 95 has completely come to rest.

In order to obtain an intimate union of the wear layer with the ballast, the latter is preferably tarred slightly before the wear layer is applied thereon. 100

What I claim and desire to secure by Letters Patent, is:—

1. A method of constructing roads which consists in superimposing on a suitable base a layer of metal stones, filling the interstices between the stones with sand, rolling down the said layer, removing the sand from the upper surface of the stones, and prior to the admission of traffic to the surface of the layer applying directly thereto a compressible layer binding covering which will be compressed substantially simultaneously with the layer thereunder by the action of the traffic 105 subsequently passing thereover.

2. A method of constructing roads which consists in superimposing on a suitable base a layer of metal stones, filling the interstices between the stones with sand, rolling down the said layer, removing the sand from the upper surface of the stones, and prior to the admission of traffic to the surface of the layer applying directly thereto a covering of tar which will be compressible substantially 110 simultaneously with the layer thereunder by the action of the traffic subsequently passing thereover.

3. A method of constructing roads which consists in superimposing on a suitable base a layer of metal stones, filling the interstices between the stones with sand, rolling down 115

the said layer, removing the sand from the upper surface of the stones, and prior to the admission of traffic to the surface of the layer applying directly thereto a compressible layer binding covering which will be compressed substantially simultaneously with the layer thereunder by the action of the traffic subsequently passing thereover, and superimposing on the compressible covering

5 a further compressible wear resisting covering which will also be compressed substantially simultaneously with the binding covering and the layer thereunder by the action of traffic subsequently passing thereover, and

10 finally under such pressure become solid.

4. A method of constructing roads which consists in superimposing on a suitable base a layer of metal stones, filling the interstices between the stones with sand, rolling down

20 the said layer, removing the sand from the upper surface of the stones, and prior to the admission of traffic to the surface of the layer applying directly thereto a covering of tar which will be compressible substantially

25 simultaneously with the layer thereunder by the action of the traffic subsequently passing thereover, and superimposing over the tar covering a further wear resisting covering of bituminized material which will also

30 be compressed substantially simultaneously with the binding covering and the layer thereunder by the action of traffic subsequently passing thereover, and finally under such pressure become solid.

35 In testimony whereof I affix my signature.
KARL DAMMANN.
